UNITED STATES PATENT OFFICE

FRANK E. AURAND, OF OAK PARK, ILLINOIS

SLOTTING MACHINE

Application filed May 26, 1926. Serial No. 111,737.

This invention relates to slotting and sawing machines which are particularly adapted for small work such as slotting commutators, wood sawing, and the like, where a fine manipulation of the cutter is necessary.

The devices of the above type are usually provided with a suitable handle at one end and a rotatable circular saw or cutter supported on a transverse spindle at the other end, the cutter being driven by an electric motor supported by the handle. Such devices have not been entirely satisfactory in the past because their general construction has not permitted the use of a comparatively small cutter for exceptionally fine work such as automotive generators and starters.

In order that a small cutter may be used, a small driving gear must of necessity be used on the shaft with such cutter in order that the latter may project away from the head of the device sufficiently to make a cut of an appreciable depth. However, if a small driving gear is attempted to be used in the devices of the past, serious difficulties are bound to be encountered in affording a construction which will stand up under the high rate of speed at which such devices must be driven and which construction may also be conveniently assembled so as to be practical to construct.

This invention aims to provide a device of the above type having an improved form of construction in which a comparatively small cutter may be used, if desired, said cutter being permitted by such construction to be driven at a high rate of speed.

In order to carry out my invention I employ a construction including a forward housing section detachable from the motor housing, a very small head on said section, a separable section of the drive shaft supported in said housing section and provided with an improved thrust bearing and oiling means therefor.

The shaft extends forwardly from said housing section and is provided with a worm on such forwardly extending portion which meshes with a worm pinion integral on a shaft journaled in a pair of forwardly extending plates detachably secured on the end

of said housing section. The pinion being integral on the shaft it may be made as small as desired. The plates in which the shaft is journaled being detachably secured to the head for purposes of assembly, convenience in assembly is not impaired by reason of said pinion and shaft being integral.

A housing completely encloses the worm and pinion between said plates forming the head and permitting said worm and pinion to run in grease or oil at all times, a feature especially advantageous for high speed devices. The cutter is mounted on the pinion shaft outside of said housing or head.

The motor housing is provided with an integral handle at one end thereof, such end being cast closed and provided with a bearing for the rear end of the armature, the other end of said housing being closed by the aforementioned detachable housing section. Said section contains a removable disc having a bearing therein for the forward end of the armature, said armature being provided with a fan rotatable therewith and adapted not only to cool the coils and bearings, but to also direct a stream of air through a suitable nozzle forwardly along said section to the cutter for cooling the latter and blowing away the shavings produced thereby.

The smaller cutter may be substituted for a larger one, if desired, for use in wood sawing, or the like, and when so used an inverted T shaped adjustable shoe is provided for attachment to the forward end of the device to permit adjusting the depth of the cut produced by the cutter, and for other purposes that will be apparent hereinafter.

Other advantageous features of my invention will be apparent from the specification and claims wherein:

Figure 1 is a fragmentary longitudinal elevational view partly in section of a device embodying this invention;

Fig. 2 is a sectional view taken at the line 2—2 of Figure 1;

Fig. 3 is a fragmentary side elevational view showing the relation of the cutter to the head;

Fig. 4 is a longitudinal elevational view showing a modified use of this invention;

Fig. 5 is a perspective view showing the inverted T shaped shoe removed from the device; and

Fig. 6 is an end view taken at the line 6-6 5 of Fig. 4.

Referring to the drawings more particularly, numeral 1 designates a cylindrical motor housing preferably of a light material, such as duralumin, or other aluminum alloy, 10 and cast integral with a handle 2. The housing 1 is cast with the right end adjacent the handle 2 closed and with the left or forward end open. A forwardly tapering housing section 3 is cast hollow with its larger end open and 15 is bolted to the housing 1 with said end communicating therewith by means of longitudinally extending diametrically spaced bolts 4.

An aluminum disc 5 is held by bolts 6 against a shoulder 7 cast integrally on the 20 inner periphery of the section 3 in a transverse plane and spaced slightly forwardly from the rear edge of said section. The disc 5 is provided with a longitudinal aperture for containing a bushing 8. The bushing 8 acts as a bearing for a connecting shaft 9. The shaft 9 is in the form of a sleeve and is 25 adapted to connect a worm shaft 10 with the armature shaft 11. The forward end of the armature shaft 11 extends into the shaft 9 and is provided with a flattened portion for 30 cooperating with a lug 12 on the shaft 9 for rotatably securing said shafts together. The other end of the armature shaft 11 is suitably supported in a bearing, not shown, in the 35 closed end of the housing 1.

The forward end of the section 3 is longitudinally apertured to receive a bushing 13 which acts as a bearing for the worm shaft 10.

A collar 14, preferably of steel, is secured 40 on the shaft 10 and acts as a thrust collar therefor. A washer 15, preferably of fiber, or other suitable material, is mounted on the shaft 10 between said collar and the bushing 13. A bronze disc 16 is loosely mounted 45 on the shaft 10 to the rear of the collar 14 and is provided with radial oil grooves 17. A second washer 18 also preferably of fiber or like material is loosely mounted on the shaft 10 between the disc 16 and a threaded 50 plug 19, which is apertured to receive said shaft and is threaded in the section 3. The plug 19 acts as a bearing for the rear end of the shaft 10 and also to keep the oil from flowing back into the after portion of the 55 section 3. The forward end of the section 3 is vertically slotted to provide a reduced portion 20 on either side of which is bolted a forwardly extending plate 21. Each of the plates 21 is provided with a transverse aperture in which is journaled a sleeve 22, preferably of bronze or other material softer than 60 steel, constituting a shaft and having a worm pinion 23 integral therewith, disposed between the plates 21 and in mesh with a worm 65 24 integral on the shaft 10. The sleeve 22 ex-

tends slightly beyond the outside of the plate 21 at either end and has frictionally secured thereto at one of said ends a circular cutter 24. The cutter 24 is secured to the sleeve 22 by means of a bolt 25, which extends 70 through the center of said cutter and the said sleeve. The cutter 24 may be secured on either end of the sleeve 22, depending upon whether the operator of the device is right handed or left handed. The profile of each of the plates 21 is substantially as shown in Figure 1 with an arcuate portion at the lower edge of said plate concentric with the pinion 23 and projecting slightly beyond the outer periphery of said pinion. The forward edge of each plate extends from the upper corner thereof to such arcuate portion and is forward of the forwardmost portion of the worm 24 or the pinion 23. Thus a plate 26 extending between the edges of the plates 21 and provided with a pair of transversely spaced flaps 27 at its upper and lower ends completely encloses the worm 24 and pinion 23 between said plates 21. Bolts 28, the same that secure the plates 21 to the section 3, extend through the flaps 27 and act to hold the plate 26 in position over the forward upper and lower edges of said plates 21.

The cylindrical housing 1 is provided with a series of circumferentially arranged apertures 29 at each end thereof. A fan 30 is splined on the armature shaft 10 adjacent the forward series of apertures 29, and is adapted to create a circulation of air through said apertures for cooling the coils and for directing a stream of air into an arcuate nozzle 31, which extends from over certain of the apertures 29 forwardly and downwardly along the periphery of the section 3 in the direction of the cutter 24.

The construction of the device is such that the driving motor within the housing 1 may be of very high speed as, for instance, 6,000 revolutions per minute. The motor within the housing 1 is driven from a source of electricity which communicates with said motor through a lead 32 extending into the bottom of the handle 2 to a trigger switch 33 and thence to said motor. The motor is preferably a universal one so that it may be conveniently used, whether the source is alternating or direct current.

In the operation of the device it needs only to be grasped by the handle 2 and the motor started by closing the switch 33. During the 120 cutting operation the device may be drawn towards the operator as well as pushed away from him. Although the cutter travels at exceedingly high speed, the worm 24 and pinion 23 will not get hot because they are continually run in grease or oil. The thrust collar 14 on the shaft 10 will not get hot due to the improved bearing and oiling means therefor. The fan 30 and nozzle 31 provides not only for the cooling of the coils and bearings 125 130

associated with the motor housing, but also provide for cooling the cutter 24, in addition to the function of blowing away the shavings from said cutter.

5. It will be obvious to those skilled in the art that the foregoing device is efficient and rugged and that the parts thereof are readily accessible for renewal and repair.

In case it is desired to use the foregoing device for wood sawing, or the like, an inverted T shaped shoe 34 is provided having a pair of vertical slots 35 in the upright portion thereof and transversely spaced from each other a distance slightly greater than the space between the plates 21. A central longitudinal slot 36 extends rearwardly from the forward edge of the shoe 34. The forward lower edges of the shoe 34 on either side of the slot 36 are beveled and knurled as shown, for a purpose that will presently be described. The plate 26 is provided with a pair of transversely spaced apertures which extend into the forward edges of the plates 21 and which are threaded to receive thumb-screws 37. The thumb-screws 37 may thus secure the shoe 34 in an adjustable manner to the forward end of the head. The forward edges of the plates 21 being slightly oblique, when the shoe 34 is secured thereto and in horizontal position, as shown in Figure 4, the device will be inclined at a convenient angle for operation, as shown in said Figure 4.

When the device is used in this manner a cutting saw 24a, usually of a much larger diameter than the cutter 24, is used. When used with the shoe 34 the device may be pivoted therewith as a unit about the knurled beveled edge at the forward end of said shoe, as for instance, when initially cutting into the floor. The depth at which the saw 24a will cut into the floor may be varied by adjusting the screws 37 in the slot 35. The knurled edges on the shoe 34 will prevent the device from kicking back as the saw 24a is entering the floor.

I am aware that many changes may be made and many details of construction varied throughout a wide range without departing from the principle of my invention, and I do not propose limiting the patent granted hereon otherwise than necessitated by the scope of the appended claims.

I claim:

1. In a machine of the character described, a housing section having its sides cut away at one end to provide lateral recesses, supporting plates fitting into said recesses and removably secured to the housing section, the supporting plates projecting forwardly beyond the end of said housing section, a shaft rotatably mounted in said plates and having one end projecting beyond the outer face of the contiguous plate, a cutter secured to the projecting end of the shaft, a drive shaft mounted in the housing section and extend-

ing between the plates, driving connections between said shafts, and a plate member disposed between said plates, said member extending about the outer edges of the plates and providing therewith a lubricant retaining housing for said driving connections.

2. In a machine of the character described, a motor including a housing, a housing section extending forwardly from the motor housing, a cutter at the forward end of said section, driving connections between the cutter and the motor, a nozzle of channel cross section disposed substantially concentric with the housing section and closely adjacent thereto with its lateral flanges bearing against said section, the outlet of the nozzle being disposed to direct a stream of air over the cutter, and means for causing air to circulate through the motor and for supplying air under pressure to the nozzle.

3. In a machine of the character described, a motor including a housing, a housing section extending forwardly from the motor housing, a cutter at the forward end of said section, driving connections between the cutter and the motor, a nozzle of channel cross section disposed substantially concentric with the housing section and closely adjacent thereto with its lateral flanges bearing against said section, the outlet of the nozzle being disposed to direct a stream of air over the cutter, and means for supplying air under pressure to the nozzle.

4. In a machine of the character described, a housing section having its sides cut away at one end to provide lateral recesses, supporting plates seating in said recesses and projecting beyond the forward end of the housing section, said plates being within the periphery of the forward end of the housing section, a first shaft rotatably mounted in the housing section and extending between the plates, a second shaft rotatably mounted in the plates, driving connections between the shafts, means for securing a tool element on the second shaft, and closure means extending between said plates and disposed flush with the outer edges thereof and providing therewith a lubricant retaining housing for said driving connections.

5. In a machine of the character described, a housing section, a driven shaft rotatably mounted in the housing section substantially axially thereof, said section being cut away from each side at its forward portion, the thickness of the forward portion of the housing section corresponding approximately to the diameter of said shaft, supporting plates seating in the lateral recesses of the forward portion of the housing section, the distance between the outer faces of said plates being within the diameter of the forward end of the housing section adjacent the cut away portion thereof, a second shaft rotatably mounted in the supporting plates, driving

- connections between the shafts, and means for securing a tool element to said second shaft.
6. In a machine of the character described, a housing section having its sides cut away at one end to provide lateral recesses, supporting plates seating in said recesses, a first shaft rotatably mounted in the housing section, a second shaft rotatably mounted in the plates, driving connections between the shafts, a closure plate spanning the space between the supporting plates, and extending about the edges of said supporting plates, the closure plate having elements extending 15 across the outer faces of the supporting plates, and securing bolts passing through said members, said bolts passing through the supporting plates and the laterally recessed portion of the housing section.
7. In a machine of the character described, a motor including a housing, a housing section extending forwardly from the motor housing and tapering toward its forward end, a cutter at the forward end of said section, 25 driving connections between the cutter and the motor, a nozzle open at its forward end and having a peripheral flange seating on the forward portion of the motor housing and on the housing section, the motor housing having air outlet openings enclosed by the nozzle, and means for causing a current of air to flow through the motor housing and through said openings into the nozzle.
8. In a machine of the character described, 35 a motor including a cylindrical housing, a housing section extending forwardly from the motor housing and tapering toward its forward end, a cutter at the forward end of said section, driving connections between the cutter and the motor, a nozzle open at its forward end and having a peripheral flange seating on the forward portion of the motor housing and on the housing section, said nozzle being arched longitudinally substantially in 40 accordance with the taper of the housing section, means for securing the nozzle in position, and means for causing a current of air to flow through said nozzle.
9. In a machine of the character described, 50 a housing section, spaced supporting plates secured to and projecting beyond said section, one of the plates being removable, a rotatably mounted shaft having its ends journaled in the plates, said shaft having an integral worm wheel disposed between the plates, a bolt secured through said shaft, means carried by the bolt and cooperating with one end of the shaft for clamping a tool to said shaft, a drive shaft, and a worm secured to the drive shaft and meshing with 55 said worm wheel.
10. In a machine of the character described, a housing section, spaced supporting plates secured to and projecting beyond said section, 60 one of the plates being removable, a rotatably mounted shaft having its ends journaled in the plates, said shaft having an integral worm wheel disposed between the plates, a bolt secured through said shaft, means carried by the bolt and cooperating with one end of the shaft for clamping a tool to said shaft, a drive shaft, and a worm secured to the drive shaft and meshing with 65 said worm wheel.
11. In a machine of the character described, a housing section, spaced supporting plates secured to and projecting beyond said section, a worm wheel disposed between the plates and having end elements journaled in said plates, and a drive shaft having an integral worm disposed between the plates and meshing with said worm wheel, the diameter of the worm corresponding to the width of the space between the plates.
12. In a machine of the character described, a housing section, spaced supporting plates secured to and projecting forwardly of said section, a worm wheel disposed between the plates and having end elements journaled in said plates and projecting beyond the outer faces thereof, a drive shaft journaled in the housing section and having an integral worm disposed between the plates and meshing with the worm wheel, said worm being of approximately the same diameter as the shaft, and a bolt passing through the worm wheel and cooperating therewith to clamp a tool to the said wheel.
13. In a machine of the character described, a housing section, spaced supporting plates projecting from the forward end of said section in alignment therewith and disposed substantially within the outline of the forward end of the housing section, a rotatably mounted worm wheel disposed entirely between the plates with its axis of rotation an appreciable distance above the bottom of the housing section, a drive shaft mounted in said housing section and provided with a worm meshing with said worm wheel, the portion of the worm which meshes with the worm wheel being disposed entirely between said plates, and closure means disposed adjacent the housing section and extending about said plates flush with the outer edges thereof and providing therewith a housing to confine a lubricant between the plates for lubricating the worm and worm wheel connection.
- In witness whereof, I hereunto subscribe my name this 10th day of May, 1926.
- FRANK E. AURAND.
